[57] CLAIM

The ornamental design for an aquarium air pump, substantially as shown.

DESCRIPTION

FIG. 1 is a top perspective view of an aquarium air pump showing our new design, with the broken lines shown for illustrative purposes only;

FIG. 2 is a side elevational view thereof;

FIG. 3 is a front elevational view thereof, the rear being substantially similar in appearance;

FIG. 4 is an opposite side elevational view thereof;

FIG. 5 is a top plan view thereof; and

FIG. 6 is a bottom plan view thereof.

FIG. 1

FIG. 2

FIG. 3

FIG. 4

FIG. 5

FIG. 6
